US00D970534S

(12) **United States Design Patent** (10) **Patent No.:** **US D970,534 S**
Wu (45) **Date of Patent:** **** Nov. 22, 2022**

(54) **DISPLAY SCREEN WITH GRAPHICAL USER INTERFACE FOR LIVE BROADCASTING**

(71) Applicant: **Twitter, Inc.**, San Francisco, CA (US)

(72) Inventor: **Veronika Wu**, San Francisco, CA (US)

(73) Assignee: **Twitter, Inc.**, San Francisco, CA (US)

(**) Term: **15 Years**

(21) Appl. No.: **29/789,781**

(22) Filed: **Oct. 18, 2021**

Related U.S. Application Data

(62) Division of application No. 29/718,938, filed on Dec. 30, 2019, now Pat. No. Des. 949,181.

(57) **CLAIM**

The ornamental design for a display screen with graphical user interface for live broadcasting, as shown and described.

DESCRIPTION

FIG. 1 is a first embodiment of a display screen with graphical user interface for live broadcasting; and, FIG. 2 is a second embodiment of a display screen with graphical user interface for live broadcasting.

The rectangular broken line in the drawings represents a display screen that form no part of the claimed design. The broken lines outside the display screen show an electronic device and form no part of the claimed design. All other broken lines inside the display screen show portions of the graphical user interface and form no part of the claimed design.

1 Claim, 1 Drawing Sheet
